UNITED STATES PATENT OFFICE

2,631,149

FOLIC ACID PRODUCTION

David I. Weisblat and Barney J. Magerlein, Kalamazoo, Mich., assignors to The Upjohn Company, Kalamazoo, Mich., a corporation of Michigan

No Drawing. Application December 3, 1948,
Serial No. 63,453

15 Claims. (Cl. 260—251.5)

1

This invention relates to a method for the preparation of N-((2-amino-4-hydroxy-6-pteridyl)methyl)-N-(arylsulfonyl)-p-aminobenzoate compounds and to certain intermediates useful in the method.

The N-((2-amino-4-hydroxy-6-pteridyl)methyl) - N - (arylsulfonyl) - p - aminobenzoate compounds which can be prepared by the method of the invention have the generic formula

wherein R' is from the group consisting of hydrogen and the alkyl radicals and n is from the group consisting of zero and the positive integers 1 to 7, inclusive, and thus include N-substitution products of p-aminobenzoic acid, of p-aminobenzoyl glutamic acid, of the p-aminobenzoyl-glutamyl-glutamic acids having up to seven glutamic acid residues in the molecule, and of their esters. In the structural formulae given herein and in the appended claims aromatic nuclei are represented by one or more simple hexagons. In the naming of compounds having the generic formula given, which are described and claimed in copending application Serial No. 41,882, filed July 31, 1948, and of other starting compounds and intermediate compounds mentioned herein wherein both a glutamic acid residue and a p-aminobenzoic acid residue are included in the molecule, the nitrogen atom of the glutamic acid residue is, for convenience, herein referred to by the symbol "N" and the nitrogen atom of the p-aminobenzoic acid residue is referred to by the symbol "N." As indicated by the generic formula, compounds used in or prepared by the process of the invention which contain more than one glutamic acid or ester residue contemplated by the invention are those wherein only the gamma-carboxyl groups are involved in the peptide linkages. Preferred compounds used in or prepared by the method of the invention are those wherein n of the generic formula given, and in those given subsequently, represents zero or the integer 1, i. e. those containing either no glutamic acid or ester residue or only one glutamic acid or ester residue, and

2

the method and intermediate compounds will be described with particular reference thereto.

be described with particular reference thereto.

Compounds having the generic formula given above and compounds useful as intermediates in the preparation thereof are of particular value due to the relationship of the former with, and to the ease with which they can be converted to, compounds similar to or identical with certain naturally occurring compounds of the folic acid group. Thus, diethyl N'-(N-(2-amino-4-hydroxy-6-pteridyl)methyl)-N-(p-toluenesulfonyl)-p-aminobenzoyl)-1-glutamate can be converted readily by hydrolysis of the two ethyl ester groups with alkali to the corresponding dicarboxy compound and the latter, by splitting the p-toluenesulfonyl radical from the molecule with hydrogen bromide and a bromine acceptor in an aliphatic acid medium, according to the method described and claimed in copending application, Serial No. 41,883, filed July 31, 1948, can be converted readily to a pteroyl-glutamic acid which appears to be identical with the "L. casei factor" or vitamin B_c from liver. The order of the hydrolysis step and splitting of the arylsulfonyl radical can be reversed, if desired.

Compounds having the generic formulae given in which the glutamic acid residues have the 1(+) configuration are of particular interest because of the existence of glutamic acid residues having the same configuration in folic acid compounds isolated from natural sources. The method of the invention and the intermediate compounds to be described are, however, not limited as to the configuration of the glutamic acid residues involved.

N-(3,3-dialkoxy-2-ketopropyl)-N-(arylsulfonyl)-p-aminobenzoate compound

N-((2-amino-4-hydroxy-6-pteridyl)methyl)-N-(arylsulfonyl)-p-aminobenzoate compound

The process of the invention, as illustrated in the accompanying reaction chart wherein the formulae of the compounds given are numbered to correspond with the following description and wherein n and R' have the values previously given, comprises, among others, the step of reacting or condensing an N-(3,3-dialkoxy-2-ketopropyl)-N-(arylsulfonyl)-p-aminobenzoate compound (IV) with 2,4,5-triamino-6-hydroxypyrimidine (V) to form an N-((2-amino-4-hydroxy-6-pteridyl)methyl)-N-(arylsulfonyl)-p-aminobenzoate compound (VI). An N-(3,3-dialkoxy-2-ketopropyl)-N-(arylsulfonyl)-p-aminobenzoate compound (IV) is prepared readily by oxidizing an N-(3,3-dialkoxy-2-hydroxypropyl)-N-(arylsulfonyl)-p-aminobenzoate compound (III), e. g. with chromic oxide. N-(3,3-dialkoxy-2-hydroxypropyl)-N-(arylsulfonyl)-p-aminobenzoate compounds (III) which are esters, i. e. wherein R' is an alkyl radical, are prepared in convenient fashion by reacting a 2,3-oxidopropanal dialkyl acetal (I) with an N-(arylsulfonyl)-p-aminobenzoate ester (II). The N-(3,3-dialkoxy-2-hydroxypropyl)-N-(arylsulfonyl)-p-aminobenzoate compounds (III) and the N-(3,3-dialkoxy-2-ketopropyl)-N-(arylsulfonyl)-p-aminobenzoate compounds (IV) which are esters, i. e. compounds wherein R' is an alkyl radical, can be converted under carefully controlled conditions to the corresponding acids, i. e. to compounds wherein R' is hydrogen, by hydrolysis with alkalies and subsequent acidification.

Certain of the N-(arylsulfonyl)-p-aminobenzoate esters (II) are described and claimed in co-pending application Serial No. 41,888, filed July 31, 1948. They can be prepared readily, as described in the copending application just mentioned, by reacting an arylsulfonyl halide with an alkyl ester of p-aminobenzoic acid, p-aminobenzoyl-glutamic acid, or a p-aminobenzoyl-glutamyl-glutamic acid having up to 7 glutamic acid residues in the molecule.

Dialkyl acetals of 1,2-oxidopropanal which can be used in the process include the dimethyl, diethyl, di-n-propyl, di-iso-propyl, dibutyl, diamyl and other dialkyl acetals. As a matter of convenience and availability dialkyl acetals wherein the alkyl radicals each contain less than 8 carbon atoms are preferred, although others can be used, if desired. It is apparent that the nature of the

alkyl groups in the 3,3-dialkyl-2-hydroxypropyl and in the 3,3-dialkyl-2-ketopropyl radicals of the intermediate compounds (III) and (IV) are determined by the particular 1,2-oxidopropanal dialkyl acetal used in the first step of the process.

Esters which can be used as starting compounds in the process, with the production of the corresponding ester intermediates, include the methyl, ethyl, n-propyl, iso-propyl, butyl, amyl, hexyl, nonyl and other alkyl esters. As a matter of convenience, alkyl esters containing less than about 8 carbon atoms in the alkyl ester radicals are preferably used in the process, although insofar as is known any alkyl ester can be used.

Although starting compounds containing substantially any arylsulfonyl radical can be used in the process of the invention and in the preparation of the corresponding arylsulfonyl intermediates and final products, the preferred starting materials and intermediate products are those containing the p-toluenesulfonyl radical due to the ready availability of the p-toluenesulfonyl halides and to the generally crystalline nature of the p-toluenesulfonyl derivatives of compounds with which the present invention is concerned. Furthermore, it appears that the p-toluenesulfonyl radical can frequently be removed from the compounds involved herein, by splitting with hydrogen bromide as mentioned previously, somewhat more readily and with the formation of a smaller proportion of undesired by-products than is the case with some of the other arylsulfonyl radicals. The invention is, however, not limited to compounds containing the p-toluenesulfonyl radical and compounds containing other arylsulfonyl radicals, such as the o-toluenesulfonyl, naphthalenesulfonyl, methylnaphthalenesulfonyl radicals and others, can be used, if desired.

It should also be mentioned that compounds containing arylsulfonyl radicals having non-hydrocarbon substituents can be used in the process and the corresponding intermediate and final products prepared, provided only that the substituent is non-reactive under the reaction conditions. Such non-reactive substituents include chlorine, bromine, and the methoxy, phenoxy, nitro and similar radicals. It should be mentioned further that, although the present invention is concerned primarily with compounds wherein the sulfonyl derivative is an arylsulfonyl derivative, the process can also be carried out and the corresponding intermediate and final products prepared using starting materials containing alkylsulfonyl, aralkylsulfonyl or cycloalkylsulfonyl radicals, such as the methanesulfonyl, ethanesulfonyl, cyclohexylsulfonyl, and phenylmethanesulfonyl radicals.

The reaction of a dialkyl acetal of 2,3-oxidopropanal with an N-(arylsulfonyl)-p-aminobenzoate ester can be carried out readily by heating the substances together, preferably with the addition of a catalytic proportion of pyridine or other tertiary amine. Approximately equimolecular proportions of the reactants can be used and the mixture preferably heated at from

about 100° to about 150° C. for from about 5 to about 60 minutes. The crude reaction mixture can be used directly in the subsequent oxidation step of the process, if desired, or the N - (3,3 - dialkoxy - 2 - hydroxypropyl) - N - (arylsulfonyl) - p - aminobenzoate compound formed can be isolated from the reaction mixture, e. g. by washing the crude reaction product thoroughly with a suitable solvent, such as naphtha or isopropanol, to remove the catalyst and unreacted starting materials. Some of the N - (3,3 - dialkoxy - 2 - hydroxypropyl) - N - (arylsulfonyl) - p - aminobenzoate esters are thus obtained as crystalline compounds having well defined melting points and some as sirupy liquids. They can be hydrolyzed to the corresponding acids by mixing with aqueous alkalies or other conventional hydrolytic agents and acidifying the aqueous reaction mixture, prefer-

ably with a mineral acid. Certain of the acids are thus obtained as solid substances.

The oxidation of an N-(3,3-dialkoxy-2-hydroxypropyl) - N - (arylsulfonyl) - p - amino-benzoate compound to an N-(3,3-dialkoxy-2-ketopropyl) - N - (arylsulfonyl) - p - amino-benzoate compound can be carried out conveniently by dissolving the hydroxy compound and chromic anhydride in glacial acetic acid and agitating the mixture for several hours, e. g. at room temperature. The reaction mixture then generally consists of a mixture of liquid and solid substances from which the ketopropyl compound can be recovered in any convenient manner. If desired, the mixture can be mixed thoroughly with ether and filtered or it can be diluted with water and then extracted with benzene or ethyl acetate. In either case, the organic layer or solution can be washed free of acid and inorganic salts with water, dried with sodium sulfate or other suitable agent and the solvent then distilled in vacuo to leave the N-(3,3-dialkoxy-2-ketopropyl) - N - (arylsulfonyl) - p - aminobenzoate compound as a sirupy residue which is generally yellowish in color.

In some instances, the product can be obtained in partially crystalline form upon allowing the oily product to stand. The crude product can, however, be used without further purification in subsequent reactions. Gentle alkaline hydrolysis of the N-(3,3-dialkoxy-2-ketopropyl)-N-(aryl-sulfonyl)-p-aminobenzoate compounds which are esters leads to the formation of the corresponding acids. The hydrolysis can be effected by mixing the ester with an aqueous or alcoholic alkali. Upon acidifying the cold aqueous reaction mixture, the acid is precipitated in the form of a solid or oily material which is generally somewhat yellowish in color. The solid compounds can be purified, if desired, by recrystallization from alcohol.

The condensation of an N-(3,3-dialkoxy-2-ke-topropyl) - N-(arylsulfonyl) - p-aminobenzoate compound with 2,4,5-triamino-6-hydroxypyrimidine to form an N-(2-amino-4-hydroxy-6-pteridyl)methyl) - N-(arylsulfonyl) - p-aminobenzoate compound can be carried out by refluxing a mixture of the substances, e. g. in a solvent such as aqueous ethanol, preferably at a pH of about 4. Alternatively, the substances can be warmed in aqueous or in glacial acetic acid solution, e. g. at from room temperature to about

120° C. for from a few minutes to a few hours. The reaction product can be recovered by distilling the solvent or by diluting the mixture with water and separating the insoluble material.

5 The product obtained is in the form of a dry powder which appears to be substantially non-crystalline in character. Reaction products which are esters can be hydrolyzed readily to the corresponding acids and, as noted previously, the arylsulfonyl radical can be removed from the molecule with hydrogen bromide.

10

The N - (3,3 - dialkoxy-2-hydroxypropyl)-N-(arylsulfonyl)-p-aminobenzoate compounds and the N - (3,3-dialkoxy-2-ketopropyl)-N-(arylsulfonyl)-p-aminobenzoate compounds having the formulae (III) and (IV), respectively, given in the reaction chart have not been described previously. They can be represented by the generic formula

wherein Y is from the group consisting of radicals having the formulae —CHOH— and —CO— and wherein n and R' have the values given previously. New compounds represented by the formula just given which can be prepared by the method herein described include, among many others, ethyl N-(3,3-dimethoxy-2-hydroxypropyl)-N-(benzenesulfonyl)-p-aminobenzoate, methyl N-(3,3-diethoxy-2-ketopropyl)-N-(p-toluenesulfonyl)-p-aminobenzoate, n-hexyl N-(3,3-di-n-propoxy-2-hydroxypropyl)-N-(o-toluenesulfonyl)-p-aminobenzoate, iso-propyl N-(3,3-di-n-hexoxy-2-ketopropyl)-N-(alpha-naphthalenesulfonyl)-p-aminobenzoate, n-butyl N-(3,3-di-n-butoxy-2-hydroxypropyl)-N-(p-chlorobenzenesulfonyl)-p-aminobenzoate, n-octyl N-(3,3-di-n-octoxy-2-ketopropyl)-N-(p-ethoxybenzenesulfonyl)-p-aminobenzoate, diethyl N'-(N-(3,3-dimethoxy-2-hydroxypropyl)-N-(benzenesulfonyl)-p-aminobenzoyl)-glutamate, dimethyl N'-(N-(3,3-diethoxy-2-ketopropyl)-N-(p-toluenesulfonyl)-p-(aminobenzoyl)-glutamate, di-n-hexyl N'-(N-(3,3-di-n-propoxy-2-hydroxypropyl)-N-(o-toluenesulfonyl)-p-aminobenzoyl)-glutamate, di-isopropyl N'-(N-(3,3-di-n-hexoxy-2-ketopropyl)-N-(alpha-naphthalenesulfonyl)-p-aminobenzoate, di-n-butyl N'-(N-(3,3-di-isobutoxy-2-hydroxypropyl)-N-(p-bromobenzenesulfonyl)-p-aminobenzoyl)-glutamate, di-n-octyl N'-(N-(3,3-di-n-nonoxy-2-ketopropyl)-N-(o-chloro-p-ethoxybenzenesulfonyl)-p-aminobenzoyl)-glutamate, N-(3,3-dimethoxy-2-hydroxypropyl)-N-(benzenesulfonyl)-p-aminobenzoic acid, N-(3,3-diethoxy-2-ketopropyl)-N-(p-toluenesulfonyl)-p-aminobenzoic acid, N-(3,3-di-n-propoxy-2-hydroxypropyl)-N-(p-ethoxybenzenesulfonyl)-p-aminobenzoic acid, N'-(N-(3,3-dimethoxy-2-hydroxypropyl)-N-(benzenesulfonyl)-p-aminobenzoyl)-glutamic acid, N'-(N-(3,3-diethoxy-2-ketopropyl)-N-(p-toluenesulfonyl)-p-aminobenzoyl)-glutamic acid, N'-(N-(3,3-di-n-hexoxy-2-ketopropyl)-N-(alpha-naphthalenesulfonyl)-p-aminobenzoyl)-glutamic acid, N'-(N-(3,3-di-n-butoxy-2-hydroxypropyl)-N-(p-chlorobenzenesulfonyl)-p-aminobenzoyl)-glutamic acid, N'-(N-(3,3-di-n-octoxy-2-ketopropyl)-N-(p-ethoxybenzenesulfonyl)-p-aminobenzoyl)-glutamic acid, N'-(N-(3,3-di-n-propoxy-2-hydroxypropyl)-N-(o-toluenesulfonyl)-p-aminobenzoyl)-glutamic acid, N'-(N-(3,3-di-n-hexoxy-2-ketopropyl)-N-(alpha-naphthalenesulfonyl)-p-aminobenzoyl)-glutamic acid.

fonyl) - p - aminobenzoyl) - glutamic acid, N' - (N - (3,3 - di - iso-butoxy-2-hydroxypropyl) - N - (p - bromobenzenesulfonyl) - p - aminobenzoyl) - glutamic acid, and N' - (N - (3,3 - di - n - nonoxy-2 - ketopropyl) - N - (o - chloro-p - ethoxybenzenesulfonyl) - p - aminobenzoyl) - glutamic acid.

Certain advantages in the invention are apparent from the following examples which are given by way of illustration only and are not to be construed as limiting.

Example 1.—Ethyl N-(3,3-diethoxy-2-hydroxypropyl) - N-(p-toluenesulfonyl)-p-aminobenzoate

A mixture of one gram of the diethyl acetal of 2,3-oxidopropanal, 1.5 grams of ethyl N-(p-toluenesulfonyl)-p-aminobenzoate and two drops of pyridine was heated for twelve minutes at 130°-135° C. The clear melt which was formed was cooled and seeded with crystals of previously prepared ethyl N-(3,3-diethoxy-2-hydroxypropyl) - N - (p-toluenesulfonyl)-p-aminobenzoate. The partially crystalline mass was triturated with a mixture of six milliliters of petroleum naphtha and three milliliters of isopropanol and the mixture filtered. There was thus obtained 1.71 grams of ethyl N-(3,3-diethoxy-2-hydroxypropyl) - N - (p-toluenesulfonyl)-p-aminobenzoate melting at 89-94° C. Repeated recrystallization of the product from isopropanol-petroleum naphtha raised the melting point to 91°-94° C. Hydrolysis of the ester with dilute alkali yields N-(3,3-diethoxy-2-hydroxypropyl)-N-(p-toluenesulfonyl)-p-aminobenzoic acid.

Example 2.—Ethyl N - (3,3 - diethoxy - 2 - ketopropyl) - N - (p-toluenesulfonyl) - p - aminobenzoate

Approximately 3.2 grams of ethyl N-(p-toluenesulfonyl)-p-aminobenzoate was reacted with the diethyl acetal of 2,3-oxidopropanal by the method described in Example 1. The crude reaction mixture prior to seeding was dissolved in 10 milliliters of glacial acetic acid and the solution mixed with a solution of one gram of chromic anhydride in 20 milliliters of glacial acetic acid. The mixture was allowed to stand at room temperature for about three hours and the acetic acid distilled in vacuo. The residue was triturated with ether and the mixture filtered. The ethereal filtrate was washed with water, dried and the ether volatilized. The residue consisted of ethyl N-(3,3-diethoxy-2-ketopropyl) - N - (p-toluenesulfonyl) - p - aminobenzoate in the form of an almost colorless oil.

N - (3,3 - diethoxy - 2 - ketopropyl) - N - (p-toluenesulfonyl)-p-aminobenzoic acid is prepared by hydrolyzing its ethyl ester or by using N - (3,3 - diethoxy - 2 - hydroxypropyl) - N - (p - toluenesulfonyl) - p - aminobenzoic acid instead of its ethyl ester in the procedure just described.

Example 3.—Ethyl N - ((2-amino-4-hydroxy-6-pteridyl)methyl) - N - (p - toluenesulfonyl)-p-aminobenzoate

A solution consisting of 100 milligrams of ethyl N - (3,3 - diethoxy - 2 - ketopropyl) - N - (p-toluenesulfonyl)-p-aminobenzoate, 296 milligrams of 2,4,5-triamino-6-hydroxypyrimidine, 1 milliliter of water and 2 milliliters of ethanol was

adjusted to pH 4.0 and refluxed for 7 minutes. The precipitate which formed was recovered by filtering and washing successively with water, alcohol and ether. The product thus recovered contained ethyl N - ((2-amino-4-hydroxy-6-pteridyl)methyl) - N - (p - toluenesulfonyl) - p - aminobenzoate. The dry product was mixed with a solution of 1 gram of sodium hydroxide in 2 milliliters of water and the mixture allowed to stand for 16 hours at room temperature. The pH of the mixture was then adjusted to 3.2 with mineral acid and the insoluble material collected by centrifuging and washed with water. There was thus obtained 25 milligrams of N - ((2-amino-4 - hydroxy - 6 - pteridyl)methyl) - N - p-toluenesulfonyl)-p-aminobenzoic acid.

Example 4.—Hydrolysis and cleavage of ethyl N - ((2 - amino - 4 - hydroxy - 6 - pteridyl)methyl) - N - (p - toluenesulfonyl) - p - aminobenzoate

The crude ethyl N - ((2-amino-4-hydroxy-6-pteridyl)methyl) - N - (p - toluenesulfonyl) - p - aminobenzoate was dissolved in 3.5 milliliters of a 26 per cent by weight solution of hydrogen bromide in glacial acetic acid and 0.13 gram of phenol was added quickly. The mixture was stirred at room temperature for one hour and then poured into 30 milliliters of anhydrous ether. After mixing thoroughly and allowing to stand for a short time, the mixture of ether and suspended solid material was filtered and the residue washed twice with anhydrous ether and then dried in vacuo for several hours. The dry residue consisted of impure ethyl N - ((2-amino-4-hydroxy - 6 - pteridyl)methyl) - p - aminobenzoate. The product was hydrolyzed with dilute sodium hydroxide to convert the ester to the free acid. The product had an activity when bio-assayed with *Streptococcus fecalis R* corresponding to a purity of 32 per cent of N - ((2-amino - 4 - hydroxy - 6 - pteridyl)methyl) - p - aminobenzoic acid.

Example 5.—Diethyl N' - (N-(p-toluenesulfonyl)-p-aminobenzoyl)-1-glutamate

Thirty and nine-tenths grams of N-(p-toluenesulfonyl)-p-aminobenzoyl chloride and 23.9 grams of diethyl 1(+) - glutamate hydrochloride were dissolved in 300 milliliters of ethylene dichloride and the solution cooled to between 0° and 10° C. The cold solution was stirred vigorously and 22.3 grams of triethylamine in 72 milliliters of ethylene dichloride was added slowly over a period of about 20 minutes. The temperature of the mixture was held between 10° and 20° C. during the addition of the triethylamine and the mixture then allowed to stand at room temperature for one hour. The mixture was then washed successively with water, dilute hydrochloric acid, saturated aqueous sodium bicarbonate and finally with water. The colorless solution thus obtained was dried with anhydrous sodium sulfate and naphtha was added until the solution became opalescent. The mixture was then cooled to cause crystallization and filtered. The crystals, after drying, consisted of 36 grams of diethyl N' - (N-(p-toluenesulfonyl) - p - aminobenzoyl) - 1 - glutamate melting at 124° to 126° C.

9

Example 6.—*Diethyl N'-(N-(3,3-diethoxy-2-hydroxypropyl)-N-(p-toluenesulfonyl)-p-aminobenzoyl)-1-glutamate*

One and six-tenths grams of the diethyl acetal of 2,3-oxidopropanal and five drops of pyridine were added to 4.77 grams of fused diethyl N'-(N - (p - tolenesulfonyl) - p - aminobenzoyl) - 1-glutamate at 140° C. The mixture was stirred for about 30 minutes at 145° to 150° C. The highly colored mass consisted chiefly of diethyl N' - (N - (3,3 - diethoxy - 2 - hydroxypropyl) - N - (p - tolenesulfonyl) - p - aminobenzoyl) - 1-glutamate. It had an index of refraction without further purification of $N_D^{30} = 1.527$. N'-(N - (3,3 - diethoxy - 2 - hydroxypropyl) - N - (p - tolenesulfonyl) - p - aminobenzoyl) - 1 - glutamic acid is formed by hydrolyzing the ester with dilute alkali.

Example 7.—Diethyl N' -(N -(3,3-diethoxy-2-ketopropyl)- N -(*p*-toluenesulfonyl)-*p*-aminobenzoyl)-1-glutamate

Five grams of diethyl N'-(N-(p-toluenesulfonyl)-p-aminobenzoyl)-1-glutamate and 1.9 grams of the diethyl acetal of 2,3-oxidopropanal were reacted substantially as by the method of Example 6. The crude diethyl N'-(N-(3,3-dimethoxy-2-hydroxypropyl)-N-(p-toluenesulfonyl)-p-aminobenzoyl)-1-glutamate thus obtained was dissolved in 35 milliliters of glacial acetic acid and 1.7 grams of chromic anhydride was added to the solution. The mixture was stirred at room temperature for about two hours and then filtered. The filtrate was diluted with water and extracted with a mixture of benzene and ethyl acetate. The organic layer was separated, washed free of acid with water and dried over anhydrous sodium sulfate. The solvent was then distilled in *vacuo* and there was thus ob-

tained 5.9 grams of diethyl N'-(N-(3,3-diethoxy-2-ketopropyl)-N-(p-toluenesulfonyl)-p-aminobenzoyl)-1-glutamate as a yellow syrup. Hydrolysis of the ester with dilute alcoholic sodium hydroxide forms N'-(N-(3,3-diethoxy-2-ketopropyl)-N-(p-toluenesulfonyl)-p-aminobenzoyl)-1-glutamate acid.

Example 8.—Diethyl N' -(N -(2-amino-4-hydroxy-6-pteridyl)methyl)- N -(p -toluenesulfonyl)- p -aminobenzoyl)-1-glutamate

A solution of 150 milligrams of 2,4,5-triamino-6-hydroxypyrimidine dihydrochloride, 115 milligrams of sodium acetate, 2.5 milliliters of water, 20 milliliters of glacial acetic acid and 415 milligrams of diethyl N'-(N-(3,3-diethoxy-2-ketopropyl)-N-(p-toluenesulfonyl)-p-aminobenzoyl)-1-glutamate were stirred in the dark at room temperature under an atmosphere of nitrogen for 45 minutes and then at 70° C. for 30 minutes. The solvent was distilled in vacuo and there remained a residue consisting principally of diethyl N'-(N-(2-amino-4-hydroxy-6-pteridyl)methyl-N-(p-toluenesulfonyl)-p-aminobenzoyl)-1-glutamate. N'-(N-(2-amino-4-hydroxy-6-pteridyl)methyl-N-(p-toluenesulfonyl)-p-aminobenzoyl)-1-glutamic acid is formed in similar manner using N'-(N-(3,3-diethoxy-2-ketopropyl)-N-(p-toluenesulfonyl)-

10

p-aminobenzoyl)-1-glutamic acid instead of its diethyl ester in the procedure just described.

Example 9.—Hydrolysis and cleavage of diethyl N' (N-((2-amino-4-hydroxy-6-pteridyl)methyl)-N-(p-toluenesulfonyl)-p-amino-benzoyl)-glutamate

The crude reaction product containing diethyl N'-(N - ((2 - amino - 4 - hydroxy - 6 - pteridyl) - 10 methyl) - N - (p - toluenesulfonyl - p - aminobenzoyl) - glutamate obtained in Example 8 was mixed with 130 milligrams of phenol and 2.5 milliliters of a 26 per cent solution of hydrogen bromide in glacial acetic acid. The mixture was 15 stirred for ninety minutes at room temperature and then diluted with anhydrous ether. Ethyl pteroyl glutamate hydrobromide separated from the mixture as a brown, hygroscopic solid which was recovered by filtration. The brown solid 20 was dissolved in about two milliliters of methanol and ten per cent aqueous sodium hydroxide was added to give a strongly alkaline solution. The alkaline mixture was allowed to stand for ninety minutes at 40° C. and then acidified with 25 mineral acid to pH 3.0. The solution was then diluted with five milliliters of water, cooled in an ice bath for one hour and then centrifuged. The solid residue was washed with three milliliters of water and three times with three milliliters of 30 acetone and dried in vacuo over sulfuric acid. There was thus obtained 89 milligrams of pteroyl glutamic acid which, upon microbiological assay with *Lactobacillus casei* had an activity of 48.8 per cent of that of the pure natural acid.

We claim:

1. The process of preparing N-((2-amino-4-hydroxy-6-pteridyl)methyl)-N-(arylsulfonyl)-p-aminobenzoate compounds which includes the step of reacting a keto acetal having the formula

wherein R' is from the group consisting of hydrogen and the alkyl radicals and n is from the group consisting of zero and the positive integer 1, with 2,4,5-triamino-6-hydroxypyrimidine to form a compound having the formula

wherein R' and n have the values given:

2. The method of claim 1 wherein n is zero.
  3. The method of claim 1 wherein n is the positive integer 1.
  4. The method of claim 1 wherein R' is hydrogen.
  5. The method of claim 1 wherein R' is an alkyl radical.
  6. The method of claim 1 wherein the alkyl radicals each contains less than 8 carbon atoms.
  7. The method of claim 1 wherein the arylsulfonyl radical is the p-toluenesulfonyl radical.
  8. The method of claim 1 wherein the keto acetal is ethyl N -(3,3-diethoxy-2-ketopropyl)- N -(p-toluenesulfonyl)-p-aminobenzoate.
  9. The method of claim 1 wherein the keto acetal is diethyl N -(N -(3,3-diethoxy-2-ketopropyl)- N -(p-toluenesulfonyl)-p-aminobenzoyl)-glutamate.

11

10. The method which includes: oxidizing an hydroxy acetal having the formula

wherein R' is from the group consisting of hydrogen and the alkyl radicals and n is from the group consisting of zero and the positive integer 1, to form a keto acetal having the formula

and, subsequently, reacting the latter compound 15 having the formula with 2,4,5-triamino-6-hydroxypyrimidine to form a compound having the formula

R' and n having the values given.

11. The method which includes: reacting a di-

alkyl acetal of 1,2-oxidopropanal with an ester

having the formula

wherein n is from the group consisting of zero and the positive integer 1, to form an hydroxy acetal ester having the formula

oxidizing the hydroxy acetal ester to form a keto acetal ester having the formula

and reacting the keto ester acetal with 2,4,5-triamino-6-hydroxypyrimidine to form a compound having the formula

n having the value given.

12. The method of claim 11 wherein a dialkyl 70 acetal of 1,2-oxidopropanal is reacted with an alkyl ester of N-(p-toluenesulfonyl)-p-aminobenzoic acid.

13. The method of claim 11 wherein a dialkyl acetal of 1,2-oxidopropanal is reacted with a di-

alkyl ester of N'-(N-(p-toluenesulfonyl)-p-aminobenzoyl)-glutamic acid.

12

14. The method which includes: reacting a dialkyl acetal of 1,2-oxidopropanal with an ester

wherein n is from the group consisting of zero and the positive integer 1, to form an hydroxy acetal ester having the formula

hydrolyzing the hydroxy acetal ester with an alkali to form an hydroxy acetal acid having the formula

oxidizing the hydroxy acetal acid to form a keto acetal acid having the formula

and reacting the keto acetal acid with 2,4,5-triamino-6-hydroxypyrimidine to form a compound having the formula

n having the value given.

15. The process according to claim 1, wherein the reactants are heated together in the presence of a solvent at a temperature below about 120 degrees centigrade.

DAVID I. WEISBLAT.
